UNITED STATES PATENT OFFICE

2,365,710

PIPE HANGER

Albert J. Loepsinger, Providence, R. I., assignor
to Grinnell Corporation, Providence, R. I., a
corporation of Delaware

Application August 27, 1943, Serial No. 500,285

1 Claim. (Cl. 248—54)

This invention relates to improvements in pipe hangers. More especially it has to do with a hanger embodying spring means.

An object of the invention is to provide a simple hanger comprising clamping means for attaching the hanger rigidly and unyieldingly to a pipe, a housing, spring means within the housing, and a tie engaging the spring means and adapted to be connected with a support.

The best mode in which I have contemplated applying the principles of my invention is shown in the accompanying drawing but these are to be taken as merely illustrative for it is intended that the patent shall cover by suitable expression in the appended claims whatever features of patentable novelty exist in the invention disclosed.

In the drawing:

Figure 1 is a vertical section, taken as on line 1—1 of Figure 2, through a pipe hanger embodying my invention;

Figure 2 is a side view of the same; and

Figure 3 is a plan view.

Referring to the drawing, the hanger comprises a plate 10 having on its under side one or more chairs 12 suitably shaped to engage the outer surface of a pipe 14 to be supported, and having one or more yokes 16 which extend around the pipe and have their ends 16a secured to the plate. As shown, there are two such yokes near opposite edges of the plate and a chair intermediate the yokes but this arrangement could be reversed with a chair near each plate edge and with a single yoke at the middle. By these clamping means the pipe is secured rigidly and unyieldingly to the hanger.

On the upper side of the plate is a housing 18 which may have a solid cylindrical wall as shown, or may be formed by upright elements having openings between them. At the outer end of the housing is a flange 18a which serves as a seat or

bottom for spring means 20 arranged within the housing.

I have here disclosed merely a simple coiled spring 20 but other spring means could be employed such as a series of nested springs and sleeves comparable to those shown in my copending application, Serial Number 495,007 filed July 16, 1943.

A bearing plate 22 rests against the yielding 10 end of the spring and is suitably shaped to provide a hemi-spherical socket 22a for a similarly shaped end 24a of a tie member 24 extending upwardly through the spring means. The tie as a whole may comprise an internally threaded 15 sleeve 26, into which the member 24 is screwed and then secured by a pin 28, and another tie member 30 can be screwed into the other end of the sleeve and secured in any desired adjusted 20 position by a lock nut 32. The upper end (not shown) of this last mentioned tie member can be attached to or connected with some suitable support.

The hanger is simple in construction, compact, economical to build, and can be readily installed 25 where desired.

I claim:

A pipe hanger comprising a tie arranged for connection with a support, a bearing plate carried by said tie, a spring coiled about a portion 30 of said tie with one end engaging the bearing plate, a housing for said spring having at one end an internal radially extending flange engaging the other end of said spring and having at the other end external laterally extending flanges, 35 a pipe-engaging chair depending from said housing intermediate said external flanges, and a yoke having its ends adjustably secured to said flanges for holding a pipe in engagement with said chair.
